VACUUM CLEANER NOZZLE

Charles T. Fromknecht, Anderson, S.C., assignor to Westinghouse Electric Corporation, East Pittsburgh, Pa., a corporation of Pennsylvania

Filed Dec. 4, 1964, Ser. No. 415,914

5 Claims. (Cl. 15—410)

This invention relates, in general, to canister vacuum cleaners and, more particularly, to a nozzle attachment for use therewith.

Most nozzle attachments are connected to a vacuum cleaner by means of a flexible hose and joined sections of metal tubing. A terminal or coupling member attached to one end of the hose serves to connect that end to the cleaner. The other end of the flexible hose is attached to one of the metal tubes while the other one of the tubes provides the connection from the first tube to the nozzle attachment.

In many instances, a section of metal tubing is permanently secured to the nozzle attachment. When this is done, the nozzle attachment becomes bulky and is thus more costly for packaging. In other instances, the tube and nozzle are packed separately to reduce packaging costs and the user is left to assemble the tube to the nozzle attachment. The assembly, however, is not permanent, therefore, the parts may be inadvertently disassembled while being used.

Accordingly, it is the general object of this invention to provide a new and improved nozzle attachment for a vacuum cleaner.

It is a more particular object of the invention to provide a new and improved nozzle attachment and tube connector which are easy to assemble and which cannot be inadvertently disassembled.

Another object of this invention is to provide a new and improved nozzle attachment which facilitates reducing the cost of packaging thereof for shipment to the user.

Further objects and advantages of this invention will become apparent as the following description proceeds and features of novelty which characterize the invention will be pointed out in particularity in the claims annexed to and forming a part of this specification.

For a better understanding of the invention, reference may be had to the accompanying drawings in which:

FIGURE 1 is a rear elevational view, partly in section, of a vacuum cleaner nozzle attachment;

FIG. 2 is a sectional view taken on the line II—II of FIG. 1;

FIG. 3 is a side elevational view of a portion of a connector tube;

FIG. 4 corresponds to FIG. 2, but has the connector tube of FIG. 3 inserted therein;

FIG. 5 is a fragmentary sectional view taken on the line V—V of FIG. 4;

FIG. 6 is a view similar to FIG. 4, but with the connector tube in a rotated position;

FIG. 7 is a fragmentary sectional view taken on the line VII—VII of FIG. 6;

FIG. 8 is a view similar to FIG. 6, but with the connector tube inserted into the nozzle attachment beyond the position shown in FIG. 6;

FIG. 9 is a view similar to FIG. 8, but with the connector tube in a second rotated position; and

FIG. 10 is a perspective view, partly in section, as viewed from the line X—X of FIG. 2.

Referring to the drawings, especially FIGS. 1 and 2, reference character 10 indicates generally a vacuum cleaner nozzle structure comprising a generally rectangular body 11 and a bottom cover plate 12 constituting the bottom face of the nozzle and which is removably at-

2

tached to the body in any suitable manner. The body and cover plate may be molded from a suitable metal or plastic material.

As best shown in FIGS. 1 and 2, the body 11 has an integrally formed enlarged housing portion 13 for receiving a connector tube 14 in a manner to be hereinafter described. The tube may be utilized to connect the nozzle to a metal conduit which, in turn, is connected to a suction device by a flexible hose of the usual type.

10 The enlarged housing portion 13 which extends to the rear of the body 11 (see FIG. 2) is provided with an axial bore 16 and a slot 17 coextensive therewith. The connector tube 14 is provided with an integrally formed or stamped projection 18 on the outer wall thereof (see FIGS. 3 and 7). As the connector tube is inserted in the bore 16 the stamped projection passes through the slot 17. A partition 19 (FIGS. 4, 5 and 10) serves to limit the travel of the tube within the housing portion 13. The partition 19 is provided with an arch-shaped opening 20 which will be discussed hereinbelow. The connector tube 14 is adapted to rotate within the bore 16 to effect engagement of the projection 18 with the top surface of a lock member 21 (best illustrated in FIG. 10). The lock member, which is biased upwardly by a leaf type spring 22 may be depressed by the projection thereby enabling further penetration of the tube into the housing portion 13 (see FIG. 8).

20 The lock member 21, made from any suitable material, for example, plastic, comprises an integral structure having an enlarged central portion 23 intermediate a pair of laterally extending wings 24. Referring to FIGS. 5 and 10, the central portion 23 is positioned between the vertical wall portions 26 of the arch-shaped opening 20 in partition 19. The laterally extending wings 24 are disposed intermediate the partition 19 and an oppositely disposed wall or partition 27. The lock member 21 is provided with a concave surface 25 which as viewed in FIGS. 7 and 10 cooperates with an arcuate portion 20 of the arch shaped opening of partition 19 to form a circular opening through the partition.

25 As viewed in FIG. 8, the connector tube can be advanced to the next position, such advancement being limited by a second partition or rib 28 having a circular opening therethrough. Since the projection no longer engages the lock member 21, the latter is free to return to its original position due to the restoring force of the spring 22. The connector tube can then be rotated to its normal operating position shown in FIG. 9. The partition 19 along with the lock member 21 as pointed out above, cooperate to form a circular opening in the partition which opening is of a smaller diameter than that of the tube 14 including the projection 28, thereby serving to permanently retain the connector tube 14 within the housing portion 13. It will be understood, therefore, that once the projection 18 is inserted beyond the lock member 21 (FIGS. 8 and 9) the connector tube cannot be withdrawn without removing the bottom cover plate 12.

30 The cover plate 12 (FIG. 2) is provided with a suction inlet 29 and has a brush member 31 suitably attached thereto, the brush member being adapted to loosen the dirt from a pile of the carpet being cleaned. As viewed in FIGS. 5 and 10, the cover plate supports the spring 22 within the housing portion 13 which spring, in turn, supports the lock member 21 for movement between a first and second position as illustrated by FIGS. 5 and 7, respectively.

35 While there has been shown and described what is at present considered to be the preferred embodiment of the invention, modifications thereto will readily occur to those skilled in the art. It is not desired therefore that the invention be limited to the specific arrangements

shown and described and it is intended to cover in the appended claims all such modifications as fall within the true spirit and scope of the invention.

What is claimed is:

1. A nozzle for a vacuum cleaner having a suction device, said nozzle comprising: a generally rectangular body member having a cover plate secured at the bottom thereof, an enlarged housing portion formed integrally with said body member and extending to the rear thereof, a connector tube for attaching the nozzle to the suction device, a projection on said tube, said enlarged housing portion being provided with a longitudinal bore and a groove coextensive therewith, said connector tube being insertable in said bore and said projection in said groove, locking means in said housing portion, first means in said housing portion for limiting travel of said tube, said projection being adapted to cooperate with said locking means for permitting insertion of said tube beyond said first limiting means, second means in said housing portion cooperating with said projection for limiting the extent of insertion of said tube beyond said first limiting means, said locking means and said first limiting means cooperating with said projection to permanently retain said connector tube in said housing portion.

2. Structure as specified in claim 1, wherein said first limiting means comprises a partition having an arch-

shaped opening delineated by an arcuate wall and a pair of vertical walls and said locking means comprises a concave surface cooperating with said arcuate wall to form a circular opening.

- 5 3. Structure as specified in claim 2 including bias means supported in said body member in operative engagement with said locking means for yieldably supporting said locking means for movement between a first and a second position.
- 10 4. Structure as specified in claim 3, wherein said projection is circumferentially non-continuous.
- 15 5. Structure as specified in claim 4, wherein said lock means comprises an enlarged central portion intermediate a pair of laterally depending wings, said enlarged central portion being disposed intermediate said vertical walls and said depending wings being captivated between said first and second limiting means.
